RAILWAY BRAKING APPARATUS

Application filed July 22, 1931. Serial No. 552,384.

Our invention relates to railway braking apparatus, and particularly to braking apparatus of the type comprising wheel engaging braking bars located beside a track rail, and movable toward and away from the rail into braking and non-braking positions. More particularly, our invention relates to apparatus of the type described in which the braking bars are arranged to be moved to their 5 braking positions by a fluid pressure operated motor, and to be restored to their non-braking positions by suitable biasing means, such as gravity. Specifically, the present invention is an improvement on apparatus of the type 10 disclosed and claimed in an application for Letters Patent of the United States filed by Herbert L. Bone on February 19, 1931, Serial No. 516,883, for railway braking apparatus.

One object of our invention is the provision in apparatus of the type described of means for normally limiting the movement of the braking bars away from the rails to an amount which is just sufficient to clear freight car wheels of ordinary width, but for at times 20 permitting sufficient additional movement of the braking bars away from the rails to clear the wide driving wheels of locomotives, thus affecting a considerable reduction in the amount of the fluid pressure which must be 25 supplied to the motor over that which would have to be supplied to the motor if the braking bars were normally moved away from the rails far enough to clear the wide driving wheels of locomotives.

We will describe one form of apparatus embodying our invention, and will then point out the novel features thereof in claims.

In the accompanying drawing, Fig. 1 is a view, partly diagrammatic and partly cross-sectioned, illustrating one form of apparatus embodying our invention. Fig. 2 is a sectional view on line II-II of Fig. 1.

Similar reference characters refer to similar parts in both views.

Referring to the drawing, the reference character 1 designates one track rail of a stretch of railway track, which track rail, as here shown, is secured to a rail support 2 mounted on an adjacent pair of the usual 50 crossties 3, only one crosstie being visible in

the drawing. Associated with the rail 1 is a car retarder comprising two braking bars A¹ and A² located on opposite sides of rail 1. Each of these braking bars comprises, as usual, a brake beam 4 and a brake shoe 5.

The braking bars A¹ and A² are arranged to be moved toward and away from the rail 1 through the medium of a lever 6 which is pivotally mounted at one end on a pivot pin 8 carried by the rail support 2, and a lever 7 which is pivotally mounted intermediate its ends on the pivot pin 8. The lever 6 is inclined upwardly and extends away from the rail 1, and is provided in its upper surface with a groove 6^a which receives the braking bar A¹. The one end 7^a of the lever 7 is likewise inclined upwardly and extends away from the rail at the opposite side of the rail from the lever 6, and the other end of 7^b and the lever 7 is inclined downwardly and extends from the rail 1 below the lever 6. The end 7^a of the lever 7 is provided in its upper surface with a groove 7^c, similar to the groove 6^a in the lever 6, which groove receives the braking bar A². The parts are so arranged and so proportioned that if the outer or free ends of the levers 6 and 7 are moved apart, the braking bars will be moved toward the rails into their effective or braking positions. When the braking bars occupy their braking positions, the brake shoes 5 will engage the opposite side faces of a car wheel traversing rail 1, and will retard the speed of the car.

The center of gravity of the lever 6 and braking bar A¹ is considerably to the left of the pivot pin 8 so that this lever will normally tend to rotate in a counter-clockwise direction about the pivot pin. Similarly, the center of gravity of the lever 7 and braking bar A² is to the right of pivot pin 8 so that this lever will normally tend to rotate in a clockwise direction about the pivot pin. It will be apparent, therefore, that when no force is applied to the free ends of the levers 6 and 7 to move them apart, the free ends of these levers will move toward each other, thereby moving the braking bars to their ineffective or non-braking positions in which they are illustrated in the drawing.

For moving the levers apart we provide apparatus embodying our invention which apparatus we will now describe. This apparatus in the form here shown, comprises a fluid pressure motor M, the cylinder 9 of which is pivotally attached to the free end of the lever 6 by means of trunnions 9^b formed on the side of the cylinder and extending through suitable openings in bifurcation 6^b formed on the lever 6, as best seen in Fig. 2. Located in the cylinder 9 is a main piston 10 and an auxiliary piston 11. The main piston 10 is attached to a piston rod 13 the free end of which is connected, by means of an adjustable eyebolt 14 and pivot pin 15, with the free end 7^b of the lever 7. It will be apparent, therefore, that simultaneous movement of the piston 10 downwardly and the cylinder 9 upwardly will move the braking bars toward their braking positions. The auxiliary piston 11 is attached to a hollow piston rod 16, and as shown in Fig. 1 is movable between a projected position, in which it is illustrated in the drawing, and a retracted position in which it engages a removable distance piece 12. The hollow piston rod 16 establishes communication between a chamber 9^a, formed at the upper end of the cylinder 9, and the region of the cylinder between the pistons 10 and 11, as will be readily understood from an inspection of the drawing. It follows that when fluid pressure is admitted to the chamber 9^a, fluid pressure will be supplied to the region of cylinder 9 between the pistons 10 and 11.

It will be plain from an inspection of the drawing that when the auxiliary piston 11 occupies its projected position, it limits the stroke of the main piston 10 and, hence, prevents the braking bars from moving as far away from the rail 1 as when the auxiliary piston occupies its retracted position. The parts are so proportioned that when the main piston 10 engages the auxiliary piston 11 in the projected position of the latter, the distance away from the rail 1 that the braking bars A¹ and A² are moved will be just sufficient to clear car wheels of ordinary width, but that, when the main piston 10 engages the auxiliary piston 11 in its retracted position, the distance away from the rails that the braking bars A¹ and A² are then moved will be sufficient to clear the usual wide driving wheels of locomotives. The function of the distance piece 12 will be explained more fully hereinafter.

The motor M is controlled by four magnet valves designated by the reference characters V¹ to V⁴, respectively, and each comprising a valve stem 17 biased to an upper position by means of a spring 18, and provided with a winding 19 and an armature 20. When valve V¹ is energized, valve stem 17 of this valve moves downwardly against the bias ex-

erted by spring 18, and a pipe 21 which communicates with the region of cylinder 9 between the auxiliary piston 11 and the distance piece 12 through a pipe 22 and a port 23 in the distance piece 12, is then connected with a pipe 24 which is constantly supplied with fluid pressure, usually air, from a suitable source not shown in the drawing. When valve V¹ is deenergized, however, valve stem 17 of this valve is moved upwardly by spring 18, and pipe 21 is then disconnected from pipe 24 and is connected with a pipe 25. When valve V² is energized, valve stem 17 of this valve moves downwardly, thereby connecting pipe 25 with a pipe 26, but when valve V² is deenergized as shown in the drawing, pipe 25 is disconnected from pipe 26. When valve V³ is energized, pipe 26 is vented to atmosphere through a port 57, but when valve V³ is deenergized, pipe 26 is disconnected from port 57. When valve V⁴ is energized, valve stem 17 of this valve moves downwardly and connects a pipe 27, which communicates with the chamber 9^a, with the pipes 21 and 22. When valve V⁴ is deenergized, however, pipe 27 is disconnected from the pipes 21 and 22, and is connected with pipe 26.

The valves V are controlled in part by a plurality of pressure responsive devices P¹⁰, P⁴⁰ and P⁷⁰, each comprising a Bourdon tube 28 connected to the pipe 27, and hence subjected to the pressure in the region of cylinder 9 between the pistons 10 and 11. Each Bourdon tube 28 controls two contacts 29—29^a and 29—29^b. The pressure responsive devices P¹⁰, P⁴⁰ and P⁷⁰ are so constructed that they will operate successively as the pressure in the region of cylinder 9 between the pistons 10 and 11 increases. For example, for all pressures below 10 pounds per square inch, contact 29—29^a of each of these devices is closed. If the pressure exceeds 10 pounds per square inch, however, contact 29—29^a of device P¹⁰ opens, and if the pressure exceeds 20 pounds per square inch, contact 29—29^b of device P¹⁰ closes. In similar manner, the pressure responsive devices P⁴⁰ and P⁷⁰ are adjusted to open their contacts 29—29^a at 40 and 70 pounds per square inch respectively, and to close their contacts 29—29^b at 50 and 80 pounds per square inch, respectively. Of course, these specific pressures are not essential but are only mentioned for purposes of explanation.

The valves V are also controlled by means of a manually operable lever L which, as here shown, is capable of assuming six positions, indicated by dotted lines in the drawing, and designated by the reference characters p¹ to p⁶, inclusive. The lever controls a plurality of contacts 30³⁻⁶, 31¹, 32¹, 33², 34⁶, 35³, 36⁴ and 37⁵. Contact 30³⁻⁶ is closed in the p³ position of the lever, the p⁶ position or any position intermediate these two positions;

contacts 31¹ and 32¹ are closed in the p^1 position of the lever; contact 33² is closed in the p^2 position of the lever; contact 34³ is closed in the p^6 position of the lever; contact 35³ is closed in the p^3 position of the lever; contact 36⁴ is closed in the p^4 position of the lever; and contact 37⁵ is closed in the p^5 position of the lever.

Lever L will usually be located at a point remote from the braking apparatus, as in the control cabin of a classification yard car retarder system and will be connected with the apparatus by means of line wires extending from the control cabin to the braking apparatus.

As shown in the drawing, lever L occupies its p^2 position, which is the position which it normally occupies when no cars are to be retarded, and all the contacts of lever L, with the exception of contact 33² are therefore open. The valves V¹, V² and V⁴ are therefore all deenergized, but valve V³ is energized over a circuit which passes from battery B through line wire 38, winding 19 of valve V³, line wire 39, wire 40, contact 33² of lever L, and common wire 41 back to battery B. Since valve V¹ is deenergized, pipe 24 is disconnected from pipe 21, and the supply of fluid pressure to all regions of cylinder 9 is therefore cut off, as will be apparent from an inspection of the drawing. Furthermore, since valves V² and V⁴ are deenergized, fluid is trapped in the region of cylinder 9 between the auxiliary piston 11 and the distance piece 12, so that the auxiliary piston 11 is held in its projected position. In addition, since valve V³ is energized and valve V⁴ is deenergized, the region of cylinder 9 between the pistons 10 and 11 is vented to atmosphere through hollow piston rod 16, chamber 9^a, pipe 27, valve V⁴, pipe 26, valve V³ and port 57, and the braking bars are therefore held by gravity in the positions in which the main piston 10 engages the auxiliary piston 11 in the projected position of the latter. The braking bars will therefore just clear freight car wheels of ordinary width. Due to the fact that the region of cylinder 9 between the pistons 10 and 11 is vented to atmosphere, all of the contacts 29—29^a of the pressure responsive devices P are closed, and all of the contacts 29—29^b are open.

In explaining the operation of the apparatus, we will first assume that the operator wishes to make a comparatively light brake application. To do this he moves lever L to its p^3 position, thereby opening contact 33² and closing contacts 33³ and 35³. The opening of contact 33² interrupts the circuit previously traced for valve V³, and valve V³ therefore becomes deenergized, thus disconnecting pipe 26 from port 57, and hence disconnecting the region of cylinder 9 between the pistons 10 and 11 from atmosphere. The closing of contact 33³ completes a circuit for valve V¹, and current flows from battery B

through line wire 39, winding 19 of valve V¹, line wire 42, contact 30³—6 of lever L, and common wire 41 back to battery B. Valve V¹ therefore becomes energized, and connects pipe 24 with pipe 21, so that fluid at full line pressure is now supplied to cylinder 9 between auxiliary piston 11 and distance piece 12 to hold auxiliary piston 11 in its projected position. The closing of contact 35³ completes a circuit for valve V⁴ passing from battery B through line wire 38, winding 19 of valve V⁴, line wire 43, wire 44, contact 29—29^a of pressure responsive device P¹⁰, wire 45, contact 35³ of lever L, and common wire 41 back to battery B. Valve V⁴ therefore also becomes energized, thus disconnecting pipe 27 from pipe 26, and connecting this pipe with pipes 21 and 22. As a result, fluid pressure is now also supplied to the region of cylinder 9 between the pistons 10 and 11, and piston 10 and cylinder 9 therefore move relative to each other in such manner that the braking bars are moved to their braking positions. As soon as the fluid in cylinder 9 between the pistons 10 and 11 reaches 10 pounds per square inch, contact 29—29^a of pressure responsive device P¹⁰ opens and interrupts the circuit just traced for valve V⁴. Valve V⁴ therefore becomes deenergized and cuts off the supply of fluid to the region of cylinder 9 between the pistons 10 and 11 until the pressure in this region of the cylinder again decreases below 10 pounds per square inch, at which time valve V⁴ will again become energized and will again admit fluid to this region of the cylinder. If the fluid in cylinder 9 between the pistons 10 and 11 increases to a pressure of 20 pounds per square inch for any reason, contact 29—29^b of pressure responsive device P¹⁰ will become closed and will complete a circuit for valve V³ which passes from battery B through line wire 38, winding 19 of valve V³, line wire 39, wire 46, contact 29—29^b of pressure responsive device P¹⁰, wire 45, contact 35³ of lever L, and common wire 41 back to battery B. Valve V³ will therefore become energized, and since contact 29—29^a of pressure responsive device will then be open so that valve V⁴ will be deenergized, the pressure in the region of cylinder 9 between the pistons 10 and 11 will be vented to atmosphere until the pressure again decreases below 20 pounds per square inch and permits contact 29—29^b of pressure responsive device P¹⁰ to open. It will be seen, therefore, that when lever L occupies its p^3 position, the braking bars will be held in their braking position by a pressure of between 10 and 20 pounds per square inch.

If the operator desires to make a more powerful brake application, he will move lever L to its p^4 position in which contacts 30³—6 and 36⁴ are closed. The operation of the apparatus, under these conditions, is similar to that just described with the following

- exceptions. Valve V^4 will now become energized over a circuit which passes from battery B through line wire 38, winding 19 of valve V^4 , line wire 43, wires 44 and 47, contact 29—29^a of pressure responsive device P^{40} , wire 48, contact 36⁴ of lever L, and common wire 41 back to battery B. When the fluid in the regions of cylinder 9 between the pistons 10 and 11 has reached a pressure of 40 pounds per square inch, contact 29—29^a of pressure responsive device P^{40} will open and will interrupt the circuit just traced for valve V^4 so that valve V^4 will become deenergized and will cut off the supply of fluid pressure to the region of cylinder 9 between the pistons 10 and 11; and if the pressure in cylinder 9 between the pistons 10 and 11 exceeds 50 pounds per square inch, contact 29—29^b of pressure responsive device P^{40} will close, and will complete another circuit for valve V^3 which passes from battery B through line wire 38, winding 19 of valve V^3 , line wire 39, wires 46 and 49, contact 29—29^b of pressure responsive device P^{40} , wire 48, contact 36⁴ of lever L, and common wire 41 back to battery B. When this latter circuit is closed, valve V^3 will again become energized and will vent the region of cylinder 9 between the pistons 10 and 11 to atmosphere until the pressure between these pistons decreases below 50 pounds per square inch. It will be apparent, therefore, that when lever L occupies its p^4 position, the braking bars will be held in their braking positions by a pressure of between 40 and 50 pounds per square inch.
- If lever L is moved to its p^5 position, valve V^1 will become energized over the circuit previously described including contact 30³⁻⁶ of lever L, and valve V^4 will become energized over a circuit which passes from battery B, through line wire 38, winding 19 of valve V^4 , line wire 43, wires 44, 47 and 50, contact 29—29^b of pressure responsive device P^{70} , wire 51, contact 37⁵ of lever L, and common wire 41 back to battery B. Fluid pressure will therefore be supplied to the region of cylinder 9 between the auxiliary piston 11 and the distance piece 12 and between the pistons 10 and 11. When the pressure of the fluid in the region of the cylinder 9 between the pistons 10 and 11 reaches 70 pounds per square inch, contact 29—29^a of pressure responsive device P^{70} will open and will de-energize valve V^4 , and if the pressure reaches 80 pounds per square inch, contact 29—29^b of pressure responsive device P^{70} will close, and will complete another circuit for valve V^3 , this latter circuit passing from battery B through line wire 38, winding 19 of valve V^3 , line wire 39, wires 46, 49 and 52, contact 29—29^b of pressure responsive device P^{70} , wire 51, contact 37⁵ of lever L, and common wire 41 back to battery B. Valve V^3 will

fluid from the region of cylinder 9 between the pistons 10 and 11 to atmosphere until the pressure again decreases below 80 pounds per square inch. It will be seen, therefore, that in the p^5 position of the lever, the braking bars are held in their braking positions by a pressure of between 70 and 80 pounds per square inch.

If it is desirable to apply still higher braking forces, the operator will move lever L to its p^6 position. Valve V^1 will then become energized over the circuit previously described including contact 30³⁻⁶ of lever L, and valve V^4 also becomes energized and will subsequently remain energized by virtue of a circuit which passes from battery B, through line wire 38, winding 19 of valve V^4 , wires 43 and 53, contact 34⁶ of lever L, and common wire 41 back to battery B. It will be apparent, therefore, that under these conditions, the braking bars will be held in their braking positions by fluid at full line pressure.

When lever L occupies any one of its p^3 , p^4 , p^5 or p^6 positions, so that the braking bars occupy their braking positions and the operator wishes to restore the braking bars to their non-braking positions in which they are illustrated in the drawing, he will restore lever L to its p^2 position. When he does this, all circuits previously traced for valve V^4 will be interrupted, and the circuit previously described for valve V^3 including contact 33² will become closed. Valve V^4 will therefore become deenergized and valve V^3 will become energized. As a result, the supply of fluid pressure to all regions of cylinder 9 will be cut off, and the fluid pressure which was previously supplied to cylinder 9 between the auxiliary piston 11 and the distance piece 12 will be trapped in this region of the cylinder to hold the auxiliary piston in its projected position in which it is illustrated in the drawing in the manner previously described. Furthermore, the region of cylinder 9 between the pistons 10 and 11 will be vented to atmosphere in the manner previously described, and the braking bars will therefore move, under the influence of gravity, to the positions in which the main piston 10 engages the auxiliary piston 11 in the projected position of the latter, which is the position in which the braking bars are illustrated in the drawing, and in which they will just clear freight car wheels of ordinary width.

We will now assume that the operator wishes to move the braking bars away from the rails far enough to permit a locomotive having the usual wide driving wheels to pass through the retarder without being engaged by the braking bars. To do this he will move lever L to its p^1 position, thereby opening contact 33², and closing contacts 31¹ and 32¹. The opening of contact 33² will interrupt the circuit for valve V^3 which was previously

closed at this contact, but the closing of contact 32¹ will complete another circuit for this valve which is similar to the circuit which was previously closed at contact 33² with the exception that this latter circuit includes contact 32¹ instead of contact 33². Valve V³ will therefore remain energized. The closing of contact 31¹ will complete a circuit for valve V² which passes from battery B through line wire 38, winding 19 of valve V², line wire 54, contact 31¹, and common wire 41 back to battery B. Valve V² will therefore become energized, and will connect pipe 25 with pipe 26. Valve V¹ will now be de- energized and, as a result, when pipe 25 becomes connected with pipe 26, the region of cylinder 9 between the auxiliary piston 11 and the distance piece 12 will become connected with atmosphere through port 23, pipes 22 and 21, valve V¹, pipe 25, valve V², pipe 26, valve V³ and port 57. The force exerted by the bias of the braking bars and the levers 6 and 7 will therefore cause pistons 10 and 11 and the cylinder 9 to move to the relative positions in which the piston 11 engages the distance piece 12, and the piston 10 engages the piston 11, thus permitting the braking bars to move away from the rails the necessary amount to clear the wide driving locomotive wheels.

It is well known that some railroads employ locomotives having unusually wide driving wheels, and when it is desired to use braking apparatus embodying our invention on these railroads, the distance piece 12 may be removed from cylinder 9 as shown in Fig. 2. The only difference that this change will make in the operation of the apparatus is that when lever L is moved to its p¹ position in the manner just described the pistons 10 and 11 and cylinder 9 instead of moving to the relative positions in which the piston 11 engages the distance piece 12 and the piston 10 engages the piston 11, will move to the relative positions in which the piston 11 engages the upper end of the cylinder 9 and the piston 10 engages the piston 11, thus providing additional opening of the braking bars, and hence permitting the braking bars to clear the unusually wide driving wheels. One advantage of this arrangement is that the same parts may be used for all railroads, thus reducing manufacturing costs.

It should also be pointed out that, since with apparatus embodying our invention, the braking bars are normally permitted to open only to the positions in which they will clear freight car wheels of usual width, the amount of fluid pressure which must be supplied to the motor to move the braking bars to other braking positions during the classification of cars is considerably less than the amount which would have to be supplied to the motor if the braking bars were normally

permitted to open sufficiently to clear the wide driving wheels of locomotives.

Although we have herein shown and described only one form of apparatus embodying our invention, it is understood that various changes and modifications may be made therein within the scope of the appended claims without departing from the spirit and scope of our invention.

Having thus described our invention, what we claim is:

1. Railway braking apparatus comprising two braking bars located on opposite sides of a track rail and biased to positions in which they will clear the wide driving wheels of locomotives, power operated means for moving said braking bars toward the rail into positions in which they will engage the wheels of a car to retard the speed of the car, and means for at times arresting the movement of said braking bars in response to their bias when the braking bars have reached the positions in which they will just clear car wheels of ordinary width.

2. Railway braking apparatus comprising two braking bars located on opposite sides of a track rail and biased to positions in which they will clear the wide driving wheels of locomotives, power operated means for moving said braking bars toward the rail into positions in which they will engage the wheels of a car to retard the speed of the car, and means for normally arresting the movement of said braking bars in response to their bias at the positions in which they will just clear car wheels of ordinary width but for at other times permitting said braking bars to move to their extreme biased position.

3. Railway braking apparatus comprising two braking bars located on opposite sides of a track rail, two levers for supporting said braking bars, said levers being pivotally supported in such manner that said braking bars are biased by gravity to positions in which they will clear the wide driving wheels of locomotives, fluid pressure means operatively connected with said levers for moving said braking bars to positions in which they will engage the wheels of a car to retard the speed of the car, and means for at times arresting the movement of said braking bars in response to their bias when the braking bars have reached the positions in which they will just clear car wheels of ordinary width.

4. Railway braking apparatus comprising two braking bars located on opposite sides of a track rail, two pivoted levers for supporting said braking bars, a cylinder connected to one braking bar, a piston in said cylinder operatively connected with the other braking bar, means for supplying fluid pressure to said cylinder to operate said

braking bar, and means for controlling the length of the stroke of said piston.

5. Railway braking apparatus comprising two braking bars located on opposite sides of a track rail, two pivoted levers for supporting said braking bars, a cylinder connected to one braking bar, a piston in said cylinder operatively connected with the other braking bar, means for supplying fluid pressure to said cylinder to operate said braking bar, and means controlled from a remote point for at times varying the length of the stroke of said piston.

6. Railway braking apparatus comprising two braking bars located on opposite sides of a track rail and movable toward and away from the rail into braking and non-braking positions, two levers for supporting said braking bars, said levers being pivotally supported for rotation about a common axis in such manner that said braking bars are biased by gravity to their non-braking positions, a cylinder connected with and supported by one of said levers, a piston in said cylinder operatively connected with the other lever in such manner that movement of said piston in one direction will move said braking bars to their braking positions, means for at times supplying said cylinder with fluid pressure in such manner that said piston is moved in said one direction, and means in said cylinder for at times limiting the movement of said piston in the opposite direction to limit the movement of said braking bars away from said track rail.

7. Railway braking apparatus comprising two braking bars located on opposite sides of a track rail and movable toward and away from the rail into braking and non-braking positions, two levers for supporting said braking bars, said levers being pivotally supported for rotation about a common axis in such manner that said braking bars are biased by gravity to their non-braking positions, a cylinder connected with and supported by one of said levers, a piston in said cylinder operatively connected with the other lever in such manner that movement of said piston in one direction will move said braking bars to their braking positions, means for at times supplying said cylinder with fluid pressure in such manner that said piston is moved in said one direction, and fluid pressure operated means for at times limiting the movement of said piston in the opposite direction to limit the movement of said braking bars away from said track rail.

8. Railway braking apparatus comprising two braking bars located on opposite sides of a track rail and movable toward and away from the rail into braking and non-braking positions, two levers for supporting said braking bars, said levers being pivotally supported for rotation about a common axis in such manner that said braking bars are biased

by gravity to their non-braking positions, a cylinder connected with and supported by one of said levers, a piston in said cylinder operatively connected with the other lever in such manner that movement of said piston in one direction will move said braking bars to their braking positions, means for at times supplying said cylinder with fluid pressure in such manner that said piston is moved in said one direction, and remotely controlled fluid pressure operated in said cylinder for at times limiting the movement of said piston in the opposite direction to limit the movement of said braking bars away from said track rail.

9. Railway braking apparatus comprising two braking bars located on opposite sides of a track rail, two pivoted levers for supporting said braking bars, a cylinder secured to one braking bar, a first piston movable in said cylinder between one end of the cylinder and an intermediate point, a second piston in said cylinder movable between the other end of the cylinder and said first piston and operatively connected with the other braking bar, and means for selectively supplying fluid pressure to said cylinder between said first piston and the adjacent end of the cylinder and to the cylinder between said pistons.

10. Railway braking apparatus comprising two braking bars located on opposite sides of a track rail, two pivoted levers for supporting said braking bars, a cylinder secured to one braking bar, a removable distance piece in one end of said cylinder, a first piston movable in said cylinder between said distance piece and an intermediate point, a second piston in said cylinder movable between the other end of the cylinder and said first piston and operatively connected with the other braking bar, and means for selectively supplying fluid pressure to said cylinder between said first piston and said distance piece and to the cylinder between said pistons.

11. Railway braking apparatus comprising two braking bars located on opposite sides of a track rail, two pivoted levers for supporting said braking bars, a cylinder secured to one braking bar, a first piston movable in said cylinder between one end of the cylinder and an intermediate point, a second piston in said cylinder movable between the other end of the cylinder and said first piston and operatively connected with the other braking bar, a first valve for controlling the supply of fluid pressure to said cylinder between said auxiliary piston and the adjacent end of the cylinder, a second valve for controlling the admission of fluid pressure to said cylinder between said pistons, and means for selectively controlling said valves.

12. Railway braking apparatus comprising two braking bars located on opposite sides of

a track rail, two pivoted levers for supporting said braking bars, a cylinder secured to one braking bar, a first piston movable in said cylinder between one end of the cylinder and an intermediate point, a second piston in said cylinder movable between the other end of the cylinder and said first piston and operatively connected with the other braking bar, a first valve for controlling the supply of fluid pressure to said cylinder between said auxiliary piston and the adjacent end of the cylinder, a second valve for controlling the admission of fluid pressure to said cylinder between said pistons, a third valve, means controlled by said second and third valves for controlling the exhaust of fluid pressure from said cylinder between said pistons, and means for selectively controlling said valves.

13. Railway braking apparatus comprising two braking bars located on opposite sides of a track rail, two pivoted levers for supporting said braking bars, a cylinder secured to one braking bar, a first piston movable in said cylinder between one end of the cylinder and an intermediate point, a second piston in said cylinder movable between the other end of the cylinder and said first piston and operatively connected with the other braking bar, a first valve for controlling the supply of fluid pressure to said cylinder between said auxiliary piston and the adjacent end of the cylinder, a second valve for controlling the admission of fluid pressure to said cylinder between said pistons, a third valve, means controlled by said second and third valves for controlling the exhaust of fluid pressure from said cylinder between said pistons, a fourth valve, means controlled by said first, third and fourth valves for controlling the exhaust of fluid pressure from said cylinder between said auxiliary piston and the adjacent end of the cylinder, and means for selectively controlling said valves.

14. Railway braking apparatus comprising two braking bars located on opposite sides of a track rail, two pivoted levers for supporting said braking bars, a cylinder secured to one braking bar, a removable distance piece in one end of said cylinder, a first piston movable in said cylinder between said distance piece and an intermediate point, a second piston in said cylinder movable between the other end of the cylinder and said first piston and operatively connected with the other braking bar, a first valve for controlling the supply of fluid pressure to said cylinder between said auxiliary piston and the adjacent end of the cylinder, a second valve for controlling the admission of fluid pressure to said cylinder between said pistons, and means for selectively controlling said valves.

15. Railway braking apparatus comprising two braking bars located on opposite sides of a track rail, two pivoted levers for sup-

porting said braking bars, a cylinder secured to one braking bar, a first piston movable in said cylinder between one end of the cylinder and an intermediate point, a second piston in said cylinder movable between the other end of the cylinder and said first piston and operatively connected with the other braking bars, a first valve for controlling the admission of fluid to said cylinder between said auxiliary piston and the adjacent end of the cylinder, a second valve, means controlled by said first and second valves for controlling the admission of fluid to said cylinder between said pistons, a third valve, means controlled by said second and third valves for controlling the exhaust of fluid from said cylinder between said auxiliary piston and the adjacent end of the cylinder, a fourth valve; means controlled by said first, third and fourth valves for controlling the exhaust of fluid for said cylinder between said auxiliary piston and the adjacent end of the cylinder, means responsive to the pressure in said cylinder between said pistons for controlling said second and third valves, and means for controlling said first and fourth valves.

16. Railway braking apparatus comprising two braking bars located on opposite sides of a track rail, two pivoted levers for supporting said braking bars, a cylinder secured to one braking bar, a first piston movable in said cylinder between one end of the cylinder and an intermediate point, a second piston in said cylinder movable between the other end of the cylinder and said first piston and operatively connected with the other braking bars, a first valve for controlling the admission of fluid to said cylinder between said auxiliary piston and the adjacent end of the cylinder, a second valve, means controlled by said first and second valves for controlling the admission of fluid to said cylinder between said pistons, a third valve, means controlled by said second and third valves for controlling the exhaust of fluid from said cylinder between said pistons, a fourth valve; means controlled by said first, third and fourth valves for controlling the exhaust of fluid from said cylinder between said auxiliary piston and the adjacent end of the cylinder, a plurality of devices responsive to the pressure in said cylinder between said pistons, a manually operable lever, means controlled by said lever for controlling said first and fourth valves, and means controlled by said lever and by said devices for controlling said second and third valves.

17. Railway braking apparatus comprising two braking bars located on opposite sides of a track rail, two pivoted levers for supporting said braking bars, a cylinder secured to one braking bar, a first piston movable in said cylinder between one end of the cylinder and an intermediate point, a second piston in said cylinder movable between the other end of the cylinder and said first piston and

- operatively connected with the other braking bars, a first valve for controlling the admission of fluid to said cylinder between said auxiliary piston and the adjacent end of the cylinder, a second valve, means controlled by said first and second valves for controlling the admission of fluid to said cylinder between said pistons, a third valve, means controlled by said second and third valves for controlling the exhaust of fluid from said cylinder between said pistons, a fourth valve; means controlled by said first, third and fourth valves for controlling the exhaust of fluid from said cylinder between said auxiliary piston and the adjacent end of the cylinder, means responsive to the pressure in said cylinder between said pistons for controlling said second valve; and means for controlling said first, third and fourth valves.
18. Railway braking apparatus comprising two braking bars located on opposite sides of a track rail and movable toward and away from the rail into braking and non-braking positions, two levers for supporting said braking bars, said levers being pivotally supported for rotation about a common axis in such manner that said braking bars are biased by gravity to their non-braking positions, a cylinder connected with and supported by one of said levers, a removable distance piece in one end of said cylinder, an auxiliary piston movable between said distance piece and an intermediate point in the cylinder, a main piston in said cylinder movable between the other end of the cylinder and said distance piece and operatively connected with the other braking bar in such manner that movement of said main piston toward said one end of the cylinder will move said braking bars toward their braking positions, four magnet valves, means effective when a first one of said valves is energized for supplying fluid pressure to said cylinder between said auxiliary piston and said distance piece, means effective when a second one of said valves and said first valve are both energized for supplying fluid pressure to said cylinder between said piston, means effective when a third one of said valves is energized and said second valve is deenergized for connecting said cylinder between said auxiliary piston and said distance piece with atmosphere, means effective when the remaining valve is energized and said first and third valves are both deenergized for connecting said cylinder between said auxiliary piston and said distance piece with atmosphere, a plurality of devices responsive to the pressure in said cylinder between said pistons, a manually operable lever, means controlled by said lever for selectively energizing said valves, and means controlled by said pressure responsive devices for controlling said second and third valves.
19. Railway braking apparatus comprising two braking bars located on opposite sides of a track rail and movable toward and away from the rail into braking and non-braking positions, two levers for supporting said braking bars, said levers being pivotally supported for rotation about a common axis in such manner that said braking bars are biased by gravity to their non-braking positions, a cylinder connected with and supported by one of said levers, a removable distance piece in one end of said cylinder, an auxiliary piston movable between said distance piece and an intermediate point in the cylinder, a main piston in said cylinder movable between the other end of the cylinder and said distance piece and operatively connected with the other braking bar in such manner that movement of said main piston toward said one end of the cylinder will move said braking bars toward their braking positions, four magnet valves, means effective when a first one of said valves is energized for supplying fluid pressure to said cylinder between said auxiliary piston and said distance piece, means effective when a second one of said valves and said first valve are both energized for supplying fluid pressure to said cylinder between said piston, means effective when a third one of said valves is energized and said second valve is deenergized for connecting said cylinder between said auxiliary piston and said distance piece with atmosphere, means effective when the remaining valve is energized and said first and third valves are both deenergized for connecting said cylinder between said auxiliary piston and said distance piece with atmosphere, a plurality of devices responsive to the pressure in said cylinder between said pistons, a manually operable lever, means controlled by said lever for selectively energizing said valves, and means controlled by said pressure responsive devices for controlling said second and third valves.
20. Railway braking apparatus comprising two braking bars located on opposite sides of a track rail and capable of assuming positions in which they will clear the wide driving wheels of locomotives, power operated means for moving said braking bars toward the rail into positions in which they will engage the wheels of a car to retard the speed of the car, and means for at times arresting the movement of said braking bar away from the rail when the braking bars have reached the positions in which they will just clear car wheels of ordinary width.
- In testimony whereof we affix our signatures.
